FUEL PUMP OF REVERSED TYPE

Filed Dec. 13, 1929

UNITED STATES PATENT OFFICE

ABRAHAM M. BABITCH AND GORDON W. HARRY, OF FLINT, MICHIGAN

FUEL PUMP OF REVERSED TYPE

Application filed December 13, 1929. Serial No. 413,768.

This invention relates to variable stroke fuel pumps for use upon the engines of automotive vehicles, and the like; and it is referred to as of a "reversed type" for the reason that (contrary to the usual arrangement) the variable-volume pump chamber is placed below the reciprocating pumping element rather than above it,—the inlet opening and the outlet opening of said chamber being at a slightly lower level still. The pumping element is preferably a diaphragm; and reciprocating movement may be conditionally imparted thereto (wherever the built-up pressure falls below a predetermined level) through a slideable handling element and by means disposed entirely above said diaphragm,—said means including a spring or pair of compression springs. These springs are preferably so housed within a novel cap as to facilitate assembly and inspection and to obviate risk of detrimental effects due to any collection of heavy deposits, or any freezing of water, about said spring or springs or said diaphragm.

Compactness and facility of assembly, of inspection and of replacement of parts are important objects of the present invention,—in which a filter unit may be disposed directly below pump parts; and advantageous embodiments thereof may accordingly include (in addition to a pair of structural elements cooperating in the retention of a pump diaphragm, one of said structural elements being preferably flanged suitably to its lateral attachment to a crankcase, or the like) not only means facilitating the separate removal of the mentioned cap and/or the mentioned cup but means facilitating the separation of said structural elements, as occasion may require,—without disturbing said cap or said cup.

It is a further object of this invention to provide a fuel pump, preferably of the self-limiting type above referred to, in which valves are located directly beneath the diaphragm and below the pump chamber in such manner as to obviate detrimental effects due to any accumulation of vapor in the region of said valves,—the stroke imparted to the diaphragm being dependent upon the

pressure built up therebelow. The position of said valves is intended to be such as to assure, with a given length of stroke, a substantially corresponding advance of fuel past said valves; and the passages to and from and between the mentioned valves are accordingly reduced to a minimum in length.

It is a further object of this invention economically to provide suitable seats for easily and reliably operated valves, said valves being preferably "loaded" by light and calibrated springs, which may be retained by suitable bosses,—said seats being preferably provided, in a novel manner, with gasket elements which obviate leakage externally past the same; and all main structural parts may be inexpensively die-cast and held together by bolts and/or screws, as illustrated.

Further objects of this invention, including various details pertaining to construction and to reliability of action, may be best appreciated from the following descriptions, taken in connection with the appended claim and the accompanying drawing.

Figure 1 may be referred to as a substantially median vertical section through one type of pump illustrative of the present invention, various optional features being included.

Figure 2 is a top plan view of the embodiment shown in Figure 1, but with certain parts broken away and certain optional features omitted.

Figure 3 is a horizontal sectional view, taken somewhat as suggested by broken line 3—3 of Figure 1.

Figure 4 is, for the most part, a sectional view corresponding to the central portion of Figure 1, but taken from a different angle and showing certain features of modification hereinafter described,—an intermediate chamber-providing element being shown as cast in one piece.

Figs. 5, 6 and 7 are partial vertical sections showing alternative details.

Referring first to the more general features shown in Figures 1, 2 and 3, a chamber-providing intermediate structural element 10 is shown as cooperating with a flanged upper

structural element 11 in the retention of a reciprocating pumping element in the form of a diaphragm 12, manipulable by a handling element in the form of a slideable rod 13; and expulsion strokes may be imparted thereto by means such as one of a pair of compression springs 14, 15 retained by means such as a cap 16 having the general form of an inverted pocket. This may be provided 10 with an inclined flange 17, cooperating with a correspondingly inclined surface provided upon the flanged structural element 11 and retained by means of screws 18.

Below the mentioned parts there is shown 15 a filter cup 19, retained by means including a pivotally movable wire bail 20, a conical element 21, and a screw 22 provided with a milled nut 23,—these features being immaterial to the present invention and fuel being 20 admitted thereto through a central inlet passage 24 in such manner that, to exit therefrom into a pump chamber 25, it must pass through a strainer or strainers held by a gasket in a known way.

25 An inlet passage 26, 26' to said chamber is shown as controlled by a valve 27; an outlet passage 28, 28' is shown as provided with a valve 29; and intake strokes may be imparted to the diaphragm 12, or its equivalent, 30 by means such as a suitable sectional lever or actuating finger F. This is shown as comprising an outer section 30, including a motion-receiving arm 31 which is engageable by a rotating or other cam 32, in a known manner, and an inner arm 33, under the constant pressure of the mentioned spring 15, or its equivalent, and also an inner section in the form of a link or a pair of links 34, 34',—slidably or otherwise connected with the diaphragm stem 13 by means of a pin 35. The mentioned lever sections are shown as pivoted upon an identical fixed pin 36; and the links 34, 34' are shown as provided with curved surfaces 37, terminating in flat surfaces 38, which are adapted to engage corresponding flat surfaces 39, provided upon the lever section 30, whenever the pressure within the pump chamber 40 falls to a value sufficiently low to enable the spring 14 to 45 depress the mentioned movable parts connected with the diaphragm 12 or the stem 13 to substantially the positions in which they are shown.

50 Except for the numerous features of modification intended to effect the advantageous results above referred to, the lever construction above described will be seen to resemble that described and claimed in the pending application of Babitch Ser. No. 304,845; filed 60 September 10, 1928; but the present invention will be seen absolutely to preclude the accumulation of any troublesome liquid in contact with the springs 14, 15; and admission of such liquids to a chamber 41, above the diaphragm 65 12 may be substantially prevented by suitable

expedients. These expedients may include the insertion of a fibrous packing element at 42 and/or the provision of an inclined drainage surface, as at 43, to permit return of any condensed liquid through an opening 44,—such as may be provided in crankcase 45, to permit reciprocation of the mentioned lever, or any suitable lever, therein. The chamber 41 may also be provided, as at 46, with an opening to the external air.

70 Although Figure 1 shows the structural element 10 as comprising an upper portion 10a, formed separately from a lower portion 10b, the latter being provided with an annular seat 47 for the filter cup 19 or for an interposed gasket 48, it is suggested in Figure 75 4 that the mentioned parts may be integrally formed or included in a single die-casting 10ab. In the form last referred to, gasoline entering through the passage 24a and descending into a filter cup (not therein shown) may rise past a valve 27a into a pump chamber 40a, descending therefrom past a valve 29a to an outlet passage 28a',—all of the mentioned passages being formed in the mentioned die-casting 10ab and valve seats being provided in any suitable way. For example, a separately inserted seat element 49a, is shown as threaded and as engaging a gasket 50a; and a "staked" seat element 51a is shown as somewhat similarly engaging a gasket 52a,—the mentioned gaskets serving to prevent leakage around the respective valve seats; and an apertured stamping 53a is optionally employed to provide a retaining boss for a calibrated spring 54a, used in connection with intake valve 27a. An analogous spring 55a is shown as surrounding an integrally formed boss 56a, below the valve 29a; and, merely to illustrate the possibility of supporting the entire organization from either of the mentioned structural elements, the element 10ab is shown as provided with a crankcase-engaging flange 57a, suitably apertured for the reception of retaining bolts or screws 58a.

75 Returning now to Figures 1 and 2, in case the structural element 10 is formed in two parts, it will be seen that the respective wells in which the valves 27 and 29 are retained may be formed by oppositely extending hollow bosses 59 and 60, one of these being formed upon each of the cooperating parts 10a and 10b. Said bosses should be substantially equal in length, interiorly machined and adapted snugly to receive oppositely-extending valve-seat bosses, and adapted to retain leakage-obviating gaskets 50 and 52, corresponding in function to the mentioned gaskets 50a and 52a; and, in this instance, the respective valve seats 49 and 51 may be economically formed integrally with the respective parts 10a and 10b of the chamber-providing structural element 10. tinct from cap-retaining screws 18 and also from diaphragm-retaining screws or bolts 18".

Figure 5 suggests the use of a reciprocating operating member in the form of a one-piece lever 3034b, replacement of spring 15 by a spring 15b, and the use of a screw 61b, provided with a special head 62b (adapting it to be automatically or manually manipulated and/or to be sealed in an adjusted position) in predetermining a limit of pressure applicable by a spring 14b,—said screw being shown as seated in the top of a cover element 16b, formed of sheet metal. The adjustment of this screw, if provided, will naturally depend upon various circumstances and especially upon the type of installation in which the described pump is to be employed; but it should be understood not only that these last-mentioned features are optional and relatively unimportant but that various features of this invention may be independently used and also that numerous modifications, additional to those suggested herein, might easily be devised,—all without departure from the scope of the present invention. For example, in the form last referred to, the cover element 16b may be formed integral with a main structural element, spring 15b being then vertically inserted in advance of screw 61b; or a very simple construction using but one spring 15c or 15d somewhat as suggested in Fig. 6 or Fig. 7, may be found satisfactory in, for example, cases where the very slight sound (sometimes caused by successive engagements of a circular or other cam with a lever 3034c or with an operating member in the form of a tappet 3034d, shown as secured by nuts 63d, 40 64d on a slidale handling element 13d and adapted to extend above a rotary cam) may not be objected to.

We claim:

In a fuel pump for lateral application to a crankcase provided with an opening through which extends an operating member: a pair of structural elements which cooperate in the retention of a diaphragm pumping element; a slidale handling element extending upward from said diaphragm element and engageable by a section of said member; and resilient means thereabove tending to hold said member against a cam and to depress said diaphragm,—the upper structural element being provided with means for drainage into said crankcase.

In testimony whereof we affix our signatures.

ABRAHAM M. BABITCH.
GORDON W. HARRY.
